WILLIAM D. COX, OF HIGHLAND PARK, ILLINOIS, ASSIGNOR OF ONE-FIFTH TO ELLEN S. COX, OF HIGHLAND PARK, ILLINOIS.

WASHING DEVICE.

1,009,830.

Specification of Letters Patent. Patented Nov. 28, 1911.

Application filed May 17, 1911. Serial No. 627,803.

To all whom it may concern:

Be it known that I, WILLIAM D. COX, a citizen of the United States, and a resident of the city of Highland Park, county of Lake, and State of Illinois, have invented certain new and useful Improvements in Washing Devices, of which the following is a specification.

My invention relates to improvements in washing devices, and more particularly to a scrubbing device adapted for use in connection with an ordinary wash board, the object of the invention being to provide a device of this character which shall materially lessen the work involved in washing clothes.

A further object of my invention is to provide a washing device which shall be simple of construction, strong and durable, and efficient in operation.

Other objects will appear hereinafter.

My invention consists in the novel construction and arrangement of parts all as will be hereinafter more fully described and particularly pointed out in the appended claims.

My invention will be best understood by reference to the accompanying drawing forming a part of this specification, and in which.

Figure 1 is a perspective view of a washing device embodying my invention, and Fig. 2 is a detail perspective view showing a scrub brush employed in the device.

The preferred form of my invention as illustrated in the accompanying drawing comprises an ordinary wash board 1 having side members 1'. The scrubbing device which is designed to co-operate with the corrugated scrubbing surface 2 of the wash board comprises a transversely disposed rectangular bar 3 having notches 4 formed in the lower edge thereof for engagement with one edge of the longitudinal members 1', said notches being adapted to guide said bar when manually moved along the edges of the side members 1'. A rod 5 substantially coextensive with the width of the wash board and adapted to slide on one edge of the members 1' is connected to the bar 3 by means of cords 6, the latter connecting the ends of said bar and rod as plainly shown in Fig. 1. A clothes clamp and scrubbing brush designed to co-operate with the bar 3 in scrubbing clothes comprises two trans-

versely disposed clamping members 7 which are held rigidly in spaced relation by means of a pair of longitudinally disposed members 8, each of the latter having a longitudinal slot 9 for a purpose to be presently described. The spacing of the members 7 is such that the bar 3 may be readily inserted therebetween when a piece of fabric or clothing 10 is placed upon said bar as plainly illustrated in Fig. 1. The scrubbing brush 11 is substantially rectangular in form and may be of a length equal to that of the member 7. This brush is mounted for longitudinal reciprocal movement on the members 8, a longitudinal slot 12 being provided in the brush for the reception of said members 8, and the fit of the latter in said slot being such as to permit of free and easy movement. In order to prevent disengagement of the brush 11 from the members 8 a pair of pins 13 is passed through said brush and the slots 9 of the members 8, there being transverse perforations 14 provided in the brush 11 for the reception of said pins. An effective scrubbing surface is provided on the brush 11 which consists in a plurality of parallel longitudinally disposed cords 15 which are secured at the ends of the brush 11 by nailing loops 16 formed in the cords as illustrated in Fig. 2. In applying the cord 15 one end of the same is first nailed to one end of the brush 11, then the cord is passed first in one direction and then in the other across the lower surface of said brush, the loops 16 being nailed after each strand is positioned as will be readily understood by those skilled in the art.

In the operation of the scrubbing device the bar 3 and rod 5 are first positioned upon the wash board 1 as shown in Fig. 1. Then the article of clothing to be washed is placed over the bar 3 and held in position thereon by means of the clothes clamp of which 7—7 are the clamp members. The scrubbing brush 11 will now be in contact with the article to be washed as shown in Fig. 1. The rod 5 is then grasped by the right hand and the scrubbing brush 11 with the left or vice versa. In moving the bar 3 upwardly and downwardly by means of the brush 11 the under side of the clothing is washed by contact with the corrugated surface 2 of the wash board. Simultaneously with the washing of this part of the clothing the upper

surface of the latter in proximity to the brush 11 is also washed, the effectiveness of the scrubbing or washing depending upon the amount of pressure exerted upon said brush by the operator. The object of the slots 9 is to permit of movement of the brush 11 independently of the rod 5 and bar 3, it being often desired to wash a small soiled spot of the garment or clothing, and in doing this it is unnecessary to rub the entire surface of the clothing. It is apparent that when the bar 3 is pulled upwardly by means of the combined action of the cords 6, rod 5 and brush 11, the lower clamping member 7 causes the clothing to be securely gripped to the lower surface of said bar, thus preventing relative movement therewith. During the downward movement of the bar 3 the upper clamping member 7 serves in clamping the clothes to said bar. It is found that the cords 15, of the scrubbing brush 11, are very efficient in performing the function required of them and that the most delicate fabrics are not injured thereby.

A scrubbing device as set forth is handy and convenient in use and efficient in operation.

While I have illustrated and described the preferred form of construction for carrying my invention into effect, this is capable of variation and modification without departing from the spirit of the invention. I therefore do not wish to be limited to the precise details of construction as set forth, but desire to avail myself of such variations and modifications as come within the scope of the appended claims.

Having described my invention what I claim as new and desire to secure by Letters Patent is:

1. The combination with a wash-board, of a transversely arranged bar slideable on said board; a clamping member engaging over said bar; and a scrubbing member slideable on said clamping member and con-

tacting with said board, substantially as described.

2. The combination with a wash-board, of a transversely arranged bar slideable on said board; a clamping member engaging over said bar; a scrubbing member slideable on said clamping member and contacting with said board; and a rod arranged above said bar and connected thereto by cords, substantially as described.

3. The combination with a wash board, of a rectangular bar transversely disposed on said wash board and adapted to reciprocate longitudinally thereon, there being notches adjacent the ends of said bars which are spaced apart corresponding with the spacing of the side members of said wash board, a cylindrical rod arranged parallel with said bar, a pair of cords connecting the ends of said bar and rod, and a clamping device adapted to coöperate with said bar comprising a pair of parallel clamping members, a pair of longitudinally disposed members passing through said clamping members and holding the latter in rigidly spaced relation, the spacing of said clamping members being greater than the width of said bar, a longitudinal slot formed in each of the members connecting said clamping members, a scrubbing brush having a slot for the reception of said slotted members, a pair of pins passing through said scrubbing brush and the slots of said slotted members, and clothes scrubbing means provided on the under surface of said brush adapted to coöperate with the corrugated surface of said wash board, substantially as described.

In testimony whereof I have signed my name to this specification in the presence of two subscribing witnesses.

WILLIAM D. COX.
